UNITED STATES PATENT OFFICE.

DAVID KAAUMOANA, OF HONOLULU, TERRITORY OF HAWAII.

PAPER-FILE.

1,162,612.

Specification of Letters Patent. Patented Nov. 30, 1915.

Application filed November 30, 1914. Serial No. 874,795.

To all whom it may concern:

Be it known that I, DAVID KAAUMOANA, a citizen of the United States, residing at Honolulu, in the county of Honolulu, Territory of Hawaii, have invented certain new and useful Improvements in Paper-Files; and I do hereby declare the following to be a full, clear, and exact description of the invention, such as will enable others skilled in the art to which it appertains to make and use the same.

This invention relates to a paper file, and the primary object of the invention is a paper file which has associated with a vertical inserting point thereof a string for stringing the bills or papers which are filed upon the file, for retaining them in specified divided lots.

Another object of this invention is to form a slot and groove in the supporting base of the paper file for receiving the string or flexible cord to permit the base to sit firmly upon a supporting structure and also for facilitating the easy attachment or detachment of a threadder cord alongside of and to the vertical inserting rod of the paper file.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and which:—

Figure 1 is a side elevation of the improved paper file. Fig. 2 is a top plan view of the paper file. Fig. 3 is a detail enlarged side elevation of the upper inserting end of the vertical inserting rod or standard of the paper file. Fig. 4 is a side elevation partially in section showing the manner of inserting and attaching the string to the vertical standard or inserting rod. Fig. 5 is a bottom plan view of the improved paper file. Fig. 6 is a sectional view through the inserting standard, and Fig. 7 is a cross sectional view on the line 7—7 of Fig. 6.

Referring more particularly to the drawings, 1 designates the base of the paper file which may be constructed of wood or other suitable material and is substantially frustoconical in shape, having its upper surface of

less diameter than the lower or supporting surface of the same. The base 1 of the paper file is provided with an opening 2 extending through the center of the same, 60 which opening is divided into substantially two equal lengths the upper length 3 of which is of greater diameter than the lower length 4, and terminates in a shoulder 5 against which the base of the vertical inserting standard 6 rests. The base 1 has a slot 7 cut therein and extending from the center of the same through the outer periphery, along the radius of the base, terminating in the vertical opening or bore 2 70 as is clearly shown in Figs. 2, 4 and 5 of the drawings. The supporting base 1 further has a groove 8 formed in the base thereof, which groove extends in alinement with the slot 7 and communicates with the bore 2. 75

The vertical standard or inserting rod 6 has its upper end sharpened as is shown at 9 to facilitate the penetrating of the point through paper, bills, letters or other suitable records of transaction which may be so filed upon the paper file. The upper pointed end 9 of the vertical inserting rod or standard 6 is bifurcated, forming a slot or opening 11 which extends downwardly therein and has its walls converging as is 85 clearly shown in Figs. 1 and 3 of the drawing.

The groove 8 and the opening 11 are provided for receiving a cord or flexible member 15 which is inserted through the bifurcated end 9 of the vertical standard 6 as is shown clearly in Fig. 4 of the drawings, and then passed inwardly in an oscillatory manner through the slot 7 until it rests in the groove 12, from whence it is bent transversely and is seated in the groove 8, extending therefrom to any suitable position, such as a ball of twine, or under a counter upon which the base 1 may be placed. The forcing downwardly of the cord or flexible member 15 between the walls of the space or opening 11 will, owing to the converging of the same tightly grip the cord and hold it securely attached to the standard 6. When the cord is properly positioned it lies 105 in abutment with the outer surface of the inserting standard 6, along substantially the entire length of the same so that when bills, letters or other records of transactions are mounted upon the standard 6 they will also 110 be mounted upon or strung upon the cord or flexible member 15, so that at the end of

the day's business, the cord or flexible member 15 may be removed from attachment to the vertical inserting standard 6 and the various bills or records of transactions will 5 be strung upon the cord or flexible member where they may be tied for separating them from the records of transactions at a previous or following date.

In reducing the invention to practice certain 10 minor features of construction, combination and arrangement of parts may necessitate alterations to which the patentee is entitled provided such alterations are comprehended within the scope of what is 15 claimed.

What is claimed is:—

1. In a file structure, the combination with a substantially frusto-conical shaped base having a slot formed therein along one 20 radius thereof, said base being further provided with a vertical bore formed centrally therein, said bore being provided with a transverse shoulder, a vertical inserting standard for insertion into said vertical 25 bore and being supported upon said transverse shoulder, a groove formed in the under surface of said base and in alinement with said slot and communicating with said vertical bore, said vertical inserting standard 30 having its upper end pointed and provided with a downwardly extending recess formed therein, said recess having its walls converging, and a flexible cord for insertion in said recess and extending downwardly along 35 said vertical inserting standard through said central bore and being seated in said

groove formed in the under surface of said base.

2. In a paper file structure, a supporting base having a slot formed therein and extending radially from the center of the same, said base further being provided with a vertical bore formed centrally therein, a vertical inserting standard having its lower end inserted in said bore, said standard having its upper end bifurcated for forming a downwardly extending recess, and a flexible cord for insertion in said recess and extending downwardly along said vertical standard through said central bore. 45

3. In a paper file structure, a supporting base having a slot formed therein and extending radially from the center of the base, said base being further provided with a vertical bore formed centrally therein, a groove 55 formed in the under surface of said base in alinement with said slot and communicating with said bore, a vertical inserting standard having its lower end inserted in said bore, said standard having its upper end bifurcated for forming a downwardly extending recess, and a flexible cord for insertion in said recess and extending downwardly along said vertical standard and through said central bore and being seated in said groove. 60

In testimony whereof I affix my signature in presence of two witnesses.

DAVID KAAUMOANA.
